Fig. 2.

Fig. 3.

Fig. 4.

Fig. 5.

Fig. 6.

FIG. 1 is a front, bottom and right end perspective view of a pushbutton switch or similar article, showing my new design;

FIG. 2 is a right end elevational view;

FIG. 3 is a left end elevational view;

FIG. 4 is a bottom plan view;

FIG. 5 is a front elevational view; and

FIG. 6 is a rear elevational view thereof.

The dominant features of the design reside in the combination on a pushbutton switch housing of a raised cross-shaped plateau on a first face and a pair of shoulders on two sides of the actuator which in effect recess the actuator which is on a face perpendicular to the first face. These features are further characterized by a pair of projecting pegs disposed on the cross-shaped plateau, with one peg near the center of the plateau and the other disposed near the center of one of the arms of the cross-shaped plateau. Additionally, the cross-shaped plateau

distinctively defines the location of a pair of holes by centering them in the arms which are perpendicular to the aforementioned arm. The actuator of the switch is a small button which projects from the center of a recessed portion on one face of the switch housing. The undisclosed face of the pushbutton switch is a substantially flat and unornamental surface.

I claim:

The ornamental design for a pushbutton switch or similar article, substantially as shown and described.
